UNITED STATES PATENT OFFICE.

FRANKLIN P. LANNON, JR., OF SAND SPRINGS, OKLAHOMA, ASSIGNOR TO AMERICAN SMELTING AND REFINING COMPANY, OF NEW YORK, N. Y., A CORPORATION OF NEW JERSEY.

METHOD AND APPARATUS FOR PRODUCING ZINC DUST.

Application filed February 1, 1927. Serial No. 165,227.

This invention relates to a method and apparatus for the production of zinc dust from zinc bearing material, and relates particularly to the method of treating the fumes 5 from a zinc retort so as to produce zinc dust of high grade and uniform quality continuously and rapidly.

When zinc bearing material is properly heated in a suitable retort of any well-known 10 type zinc fumes or vapor is produced which is then introduced into a chamber or condenser having a relatively large volume compared to the retort and having a temperature in some portion thereof below the coalescing 15 and condensing point of the vapor. Ordinarily the vapor is allowed to disseminate gradually through the condenser chamber or receptacle at a rate determined by the currents induced by the incoming fumes, its 20 condensation into dust, and various other factors. Under such circumstances the portion of the chamber or condenser near the inlet from the retort becomes heated to a high temperature approximating the temperature of the retort.

This invention relates to a method and means for reducing the temperature of the portion of the condensing chamber at and adjacent to the inlet from the retort by producing and maintaining a comparatively 30 rapid and continuous circulation of any vapor within the condenser, thereby subjecting the incoming fumes to a maximum initial drop in temperature, and in effect equalizing the temperature throughout the condenser 35 and establishing a lower average temperature for the condensing chamber as a whole.

The invention also provides for circulating the vapor from one portion of the condenser to another portion thereof through a suitable conduit which may be in whole or in part external to the condenser and by means of the radiating surface of said conduit contribute to the rapid cooling of the 45 vapor.

The invention further consists in the new and novel features of operation and combinations of steps in the process hereinafter described and also in the new and novel features of construction and combinations of parts, hereinafter set forth and claimed.

In the accompanying drawings I have

shown for purposes of illustration one form of mechanism with certain modifications thereof adapted for practicing my invention, 55 in which

Fig. 1 is a diagrammatic representation in elevation of a zinc retort, a condenser, a conduit therebetween and a fan mounted within the condenser for circulating zinc vapors 60 therein;

Fig. 2 is a similar diagrammatic representation with the fan shown mounted at the opening of the condenser, through which the conduit from the retort discharges; 65

Fig. 3 is a diagrammatic plan view of a retort connected to a condenser through a by-pass pipe in which is positioned a fan 70 adapted to carry the zinc fumes from one part of the condenser to another; and

Fig. 4 is a diagrammatic plan view similar to Fig. 3 showing a zinc fume condenser having a manifold thereon in which is positioned a fan and from which by-passes extend to other parts of the condenser. 75

In the following description and in the claims parts will be identified by specific names for convenience but the terms are intended to be as generic in their application to similar parts as the art will permit. 80

As diagrammatically indicated in Fig. 1 of the drawings, the zinc retort 1 may be of standard shape and material. It is connected by a suitable outlet or conduit with a condenser 2, which has a relatively large volume 85 compared to the retort and may be of standard construction providing a considerable radiating surface. Within the condenser 2 is mounted suitable means for producing continuous and comparatively rapid circulation 90 of any fumes within the condenser, such, for example, as an electrically operated fan 4. Said fan is shown in Fig. 1 as being positioned to deflect the zinc fumes in a current transversely across the condenser where they will 95 strike the condenser walls and will be deflected along said walls at a high rate of speed to produce a rapid transmission of heat from said fumes to the condenser walls. Such rapid movement of the fumes and of the condensed particles will produce finely divided zinc dust because the incipient dust particles as they form from the fumes will be quickly cooled to a temperature below that at which 100

the hot fumes or vapor usually fuses or coalesces to form larger particles.

In Fig. 2 is shown another embodiment of my invention in which the fan 4 is mounted in the condenser at the inlet from the retort. In this position the zinc fumes move at a high rate of speed with a driving force from the instant they enter the condenser until they are deposited as condensed particles in the bottom of the condenser.

In Fig. 3 is shown still another embodiment of my invention in which the zinc retort 1 connects to the condenser 2 through the conduit 3. A by-pass pipe 5 extends from an upper part of the condenser 2 to a lower part, and has mounted therein the fan 4 adapted to draw zinc fumes from the condenser 2 into the upper end of the by-pass 5 through which they are driven at a high rate of speed and cooled against the sides of the by-pass from which they are discharged in the cooled and finely divided solid state.

It is to be understood that the by-pass may be multiplied as to number and that foregoing fans may be positioned within the by-pass tubes or one or more fans may be positioned in the condenser 2 proper at either end of the by-pass or by-passes.

In Fig. 4 is illustrated in plan view a zinc retort 1 connecting with the zinc fume condenser 2 through the conduit 3. A manifold 6 opening from the side of the condenser 2 near its top has extending therefrom the by-passes 8, 8 which connect into the condenser 2 at points below the manifold 6. A fan 4 in the manifold serves to drive zinc fumes from the upper part of the condenser 2 through the by-passes 6 into the lower part of the condenser, whereby as they pass through the by-passes they are quickly cooled below the vaporizing temperatures.

In the use and practice of my invention zinc fumes are cooled in a condenser to produce minutely subdivided zinc dust by circulating them as they enter the condenser. Cooling is efficiently and quickly produced by intermingling hot fumes which have just entered the condenser with cooler fumes from a part of the condenser remote from the fume entrance point thereof. Also, cooling is attained by circulating fumes from the point of entry in the condenser over heat conducting surfaces of the condenser, as for example by rapidly and vigorously circulating the fumes from the hot zone in the condenser through by-pass conduits having comparatively large cooling surfaces and into a cooler zone in the condenser. In this manner there is achieved a rapid cooling of the fumes whereby they are condensed into zinc particles having a very small mass, the formation of particles of larger masses being precluded by the rapidity with which they are formed or condensed from the fumes.

65 Although the novel features of the inven-

tion have been pointed out in the annexed claims, it will be understood that various omissions, substitutions and changes in the forms and details of the device illustrated and in its operation may be made by those skilled in the art without departing from the spirit of the invention.

What is claimed is:

1. The method of producing zinc dust in a state of minute subdivision from zinc fumes which comprises circulating the zinc fumes vigorously and rapidly to cool them quickly to a point considerably below the vaporizing temperature whereby the zinc particles are solidified as they are incipiently condensed and formed.

15 2. The method of producing zinc dust in a finely divided state which consists in distilling zinc bearing metal to produce zinc fumes, passing the fumes into a condensing space, and rapidly circulating said fumes within said space at a temperature below the vaporizing point of the zinc, whereby the zinc particles are solidified as they are incipiently condensed and formed.

20 3. The process of equalizing the temperature in a zinc fume condenser which consists in receiving zinc vapors in the form of fumes and producing currents of fumes circulating about the walls of the condenser at a relatively high velocity.

25 4. The method of producing fine zinc dust which consists in continuously circulating zinc vapor from a zone at a relatively high temperature in a condenser through a normally cooler zone of the condenser.

30 5. The process of producing a rapid initial drop in temperature of zinc fumes introduced into a condenser from a retort which consists in continuously commingling with the vapor admitted from the retort relatively cooled vapor from a relatively cool portion of the condenser.

35 6. The method of producing fine zinc dust which comprises receiving zinc fumes into a condenser and vigorously circulating the fume in the condenser, whereby the zinc fume is condensed into fine zinc dust.

40 7. The method of producing finely divided zinc powder which comprises heating zinc bearing material to volatilize zinc therefrom, passing the zinc fumes into a condenser, and circulating the fumes within the condenser and against the condenser walls at a high rate of speed, whereby the zinc fumes are cooled rapidly and pass quickly into the solid state without substantial coalescing of the minute condensed particles of zinc.

45 8. In combination, a zinc distilling means, a zinc fume condenser connected therewith and means for producing rapid and continuous circulation of fumes within the said condenser.

50 9. In combination, a zinc retort, a condenser connected thereto, and means in said

condenser adapted for circulating zinc fumes within and against the sides of the condenser.

10. In combination with a zinc fume condenser, means mounted in the upper part thereof adapted to drive the zinc fumes at a high rate of speed from the upper part of the condenser to the lower part thereof and against the surface thereof.

11. In combination with a zinc fume condenser, means mounted in the upper part thereof adapted to drive the zinc fumes at a high rate of speed from the upper part of the condenser to the lower part thereof.

In testimony whereof I have hereunto set 15
my hand.

FRANKLIN P. LANNON, JR.
